Office Action issued Jun. 13, 2025 in related U.S. Appl. No. 30/002,410.

Primary Examiner — Patricia A Palasik

(74) *Attorney, Agent, or Firm* — XSENSUS LLP

(57) **CLAIM**

The ornamental design for a cutting tool, as shown and described.

DESCRIPTION

FIG. 1 is a front view of a cutting tool in accordance with my design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is an end view taken along line 9-9 of FIG. 1;

FIG. 10 is an end view taken along line 10-10 of FIG. 1;

FIG. 11 is an enlarged view of FIG. 9; and,

FIG. 12 is an enlarged view of FIG. 10.

The broken lines in the drawings depict portions of the cutting tool which form no part of the claimed design.

1 Claim, 6 Drawing Sheets
